UNITED STATES PATENT OFFICE.

JAMES READMAN, OF NORTON, COUNTY OF DURHAM, ENGLAND.

MARINER'S AND AZIMUTH COMPASS.

SPECIFICATION forming part of Letters Patent No. 243,460, dated June 28, 1881.

Application filed March 28, 1881. (No model.) Patented in England December 1, 1880.

To all whom it may concern:

Be it known that I, JAMES READMAN, of Norton, county of Durham, England, have invented certain new and useful Improvements 5 in Mariners' and Azimuth Compasses, of which the following is a specification.

This invention forms the subject of Letters Patent granted to me in Great Britain, dated December 1, 1880, No. 5,007.

10 In mariners' and azimuth compasses as now made and used the motions of the compass-cards produce currents of air within the compass-bowl, so that the compass cannot be relied upon to give a true indication; and this 15 is equally true in compasses wherein oil, glycerine, and other dense liquids are employed in lieu of air. The movement of the card produces currents, and the denser liquids acquire a momentum when set in motion which serves 20 to deflect the needle.

The object of my invention is to remedy this defect, and for this purpose I cause the compass-card to move in a vacuum, so that being shielded from external influences the 25 north pole of the magnetic needle will then always point truly to the north magnetic pole of the earth.

In carrying out my invention I cover the compass-bowl hermetically with a sheet of 30 plate-glass of sufficient strength to bear the atmospheric pressure, and then, by means of an air-pump or suitable exhausting apparatus, I produce as perfect a vacuum as possible within the compass-bowl.

35 One method of producing and maintaining a vacuum in the compass-box is represented in Figure 1 of the annexed drawings, which is a vertical section of a mariner's compass.

a is the bowl, and *b* the card, pivoted in any 40 ordinary manner.

c is a sheet of plate-glass, with which the bowl is hermetically covered, and which is strong enough to bear the atmospheric pressure.

45 *d* is a screw-ring to secure the plate *c* in position.

In the bottom of the bowl I drill a vertical hole, *e*, about one-eighth of an inch in diameter, more or less, also a horizontal hole, *e'*, 50 of like diameter, extending from the side of

the bowl to the bottom of the hole *e*. I then make the hole *e'* of conical form, as shown, and I insert into it a brass or other soft-metal tube, *f*, the inner end of which I solder into the hole *e'*. The glass *c* having been secured 55 in place, I connect the tube *f* with an air-pump and produce a vacuum in the bowl *a*. When the vacuum is formed I compress the sides of the tube *f*, as indicated in dotted lines, by means of pliers or other suitable tool, so as to 60 hermetically close it, and I then sever the tube outside the compression, after which I solder up the hole *e'* so as to make it flush with the surface of the bowl.

Fig. 2 represents in vertical section, and 65 Fig. 3 in elevation, taken at right angles to Fig. 2, a somewhat modified way of producing and maintaining the vacuum in the compass-box.

g is a hoop or ring which exactly fits the 70 outside of the bowl. I drill a hole, *ee'*, through the hoop *g* and through the side of the bowl *a*, and I screw or otherwise fix into the hole *e'* in the hoop a tube, *f*, which I connect with the air-pump. After having produced the required vacuum in the bowl I turn the hoop *g* 75 partly round, so as to bring an unperforated part opposite the hole *e*, and thereby close the hole. To insure that the closing shall be hermetic, the part of the hoop moved over the 80 hole may be faced with leather or other like suitable material. I then fix the hoop in place by running solder into the hole *e'* and into three or other suitable number of other holes, *e''*, which I form for the purpose in the hoop. 85

I am aware that a compass-box has been constructed with an annular wall around it, from the cavity in which the air has been abstracted, the object being to reduce the aberration resulting from local attraction; but 90 I am not aware of a compass-card having been arranged to move in a vacuum, as herein described.

I am also aware that the movement of the needle-card in a vacuum will render it less 95 stable and more sensitive than when it moves in air, or in some denser liquid, as oil or glycerine; and should it be found too sensitive this may be corrected by an increase of friction at the pivot. 100

What I claim, and desire to secure by Letters Patent, is—

1. As an improved article of manufacture, a mariner's or azimuth compass having its card arranged to move in a vacuum, substantially as and for the purposes set forth.

2. An azimuth or mariner's compass comprising an air-tight box with a glazed or transparent top, from which box the air has been exhausted, and a compass-card and needle

mounted rotatively on a pivot within said box, substantially as described.

In witness whereof I have hereunto signed my name in the presence of two subscribing witnesses.

JAMES READMAN.
